UNITED STATES PATENT OFFICE.

FREDERICK THOMAS WALKLETT, OF TUNSTALL, ENGLAND, ASSIGNOR TO RUDOLF GAERTNER, OF NEW YORK, N. Y.

DESIGN FOR AN ARTICLE OF MANUFACTURE.

46,075.

Specification for Design.

Patented July 7, 1914.

Application filed March 27, 1914. Serial No. 827,765. Term of patent 3½ years.

To all whom it may concern:

Be it known that I, FREDERICK THOMAS WALKLETT, a citizen of the Kingdom of Great Britain, and resident of Tunstall, Staffordshire, England, have invented a new, original, and ornamental Design for an Article of Manufacture, of which the following is a specification, reference being had to the accompanying drawing, forming part thereof.

The figure is a plan view illustrating my new design to be applied to an article of manufacture.

I claim:

The ornamental design for an article of manufacture, as shown.

FREDERICK THOMAS WALKLETT.

Witnesses:

ARTHUR MACHIN,
PATTIE PLANT.
